UNITED STATES PATENT OFFICE.

JOHN W. GREEN, OF SANTA FE, TERRITORY OF NEW MEXICO.

DESIGN FOR A BADGE.

No. 40,002.

Specification for Design.

Patented May 25, 1909.

Application filed March 15, 1909. Serial No. 483,652. Term of patent 14 years.

To all whom it may concern:

Be it known that I, JOHN W. GREEN, a citizen of the United States, and a resident of Santa Fe, in the county of Santa Fe and Territory of New Mexico, have invented a new, original, and ornamental Design for a Badge, reference being had to the accompanying drawing, in which the figure is a front view of the badge, showing my new design.

I claim—
The ornamental design for a badge as shown.

JOHN W. GREEN.

Witnesses:

SAMUEL B. GRIMSHAW,
CHARLES CHRISTMAN.
